CLAIM

The ornamental design for a cap for a container, as shown and described.

DESCRIPTION

FIG. 1 is a top and right perspective view of a cap for a container;

FIG. 2 is a bottom and left perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines are included for the purpose of illustrating environmental structure and form no part of the claimed design.
